DESIGN FOR A SHOE OR SIMILAR ARTICLE

Robert Richard Bunting, Paris, France

Application October 9, 1936, Serial No. 65,223

Term of patent 3½ years

To all whom it may concern:

Be it known that I, Robert Richard Bunting, a citizen of the Kingdom of Great Britain, residing in Paris, France, 233, rue St-Honoré, have invented a new, original, and ornamental Design for a Shoe or Similar Article, of which the following is a specification, reference being had to the accompanying drawing, forming part thereof:

I claim:

The ornamental design for a shoe or similar article, substantially as shown.

ROBERT RICHARD BUNTING.
